(57) **CLAIM**

The ornamental design for a motion sensor with microphone, as shown and described.

DESCRIPTION

FIG. 1 is a perspective view of a motion sensor with microphone showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showings of various regions of the motion sensor with microphone and the unshaded areas therein in FIGS. 1–7 are for environmental purposes only and form no part of the claimed design.
